UNITED STATES PATENT OFFICE.

ARTHUR H. WRIGHT, OF MINNEAPOLIS, MINNESOTA.

ROTARY RECIPROCATING ENGINE.

Application filed April 16, 1926. Serial No. 102,439.

My invention has for its object to provide an improved engine of the type wherein reciprocating motion produced by cylinder and cooperating pistons is converted into rotary motion in the engine proper and without the use of cranks and cooperating connecting rods. Especially, this engine has been designed for use as an internal combustion engine, but the broader features involved therein may be used in engines wherein steam or compressed air is the motive fluid.

In accordance with my invention, I employ a nonrotary casing or outer support, a cylinder structure arranged to rotate within said casing or support, pistons arranged to reciprocate within the cylinder structure while rotating therewith, and an obliquely set connecting ring arranged to 20 rotate within the support or outer casing and having such connections to the cylinders and pistons that reciprocating motion of the latter will cause the cylinders and the pistons to rotate. This arrangement permits rotary motion to be taken directly off from the rotating cylinder structure.

An embodiment of the invention is illustrated in the accompanying drawings, wherein like characters indicate like parts throughout the several views.

Referring to the drawings:

Fig. 1 is a horizontal section taken axially through the engine;

Fig. 2 is an oblique section taken on the line 2—2 of Fig. 1;

Fig. 3 is a transverse section taken on the line 3—3 of Fig. 1, some parts being broken away and some parts removed;

Fig. 4 is a transverse section taken on the line 4—4 of Fig. 1;

Fig. 5 is a transverse section taken on the line 5—5 of Fig. 1; and

Figs. 6, 7 and 8 are diagrammatic views chiefly in axial section, illustrating different positions of the cylinder, sleeve piston and pistons proper.

Directing attention first to Figs. 6, 7 and 8, it will be noted that the primary movable elements of the engine are a long cylinder 9, a sleeve piston 10, and pistons proper 11, the latter being connected by a connecting bar or member 12. The sleeve piston 10, as will hereinafter appear, operates both as a piston and as a cylinder. It is arranged to reciprocate within the cylinder proper 9 and the pistons 11 are arranged

to work within the opposite ends of said sleeve piston.

By means presently to be described, the cylinder 9, sleeve piston 10 and pistons 11 are arranged to partake of a common rotary motion on the common axis thereof.

By reference particularly to Fig. 1, it will be noted that the cylinder 9 has rigidly secured heads 13 to which shafts 14 are rigidly secured and arranged to project axially therefrom. These shafts 14 are journaled in the yoke-like end portions 15 of a nonrotary or fixed outer shell made up of an intermediate section 16 and end sections 17. Interposed between and rigidly secured to the flanged abutting ends of the sections 16 and 17 are annular joint plates 18 that have close beveled engagement with beveled flanges 19 secured on the rotary cylinder 9, as best shown in Fig. 1.

The cylinder heads 13 are provided with ports normally closed by lightly sprung closed inwardly opening check valves 20. The valves 20 normally close fuel intake ports 21 formed partly in said heads 13 and partly in diametrically spaced longitudinally extended intake tubes 22 that are secured to the exterior of the cylinder 9 and open through the flanges 19 of said cylinder 9. Here it may be stated that the explosive mixture, preferably supplied from a suitable carburetor 23, is taken into the annular fuel chamber 16 formed within the intermediate shell section 16 between 85 the joint plates 18.

The rotary cylinder 9, outward of the annular joint plates 18, is provided with circumferentially spaced exhaust ports 24 indicated by dotted lines in Fig. 1 and by full lines in Fig. 5; and in the plates of these two series of ports, the outer shell sections 17 are formed with spiral exhaust channels 25 shown in Figs. 1 and 5.

For cooperation with the cylinder ports 24, the sleeve piston 10 is formed with corresponding circumferentially spaced exhaust ports 26 which, at the right in Fig. 1, are shown as registered with the cooperating ports 24, but, at the left, are shown out of registration with their cooperating cylinder ports 24.

At opposite ends, the sleeve piston 10 is provided with heads 27 having admission ports normally closed by inwardly opening check valves 28. These check valves 28 are mounted for limited sliding movements in

the respective heads 27 and have cylindrical bodies formed with circumferentially spaced ports. The beveled joint flanges 19 on the rotary cylinder 9, adjacent to the intake ends of the admission ports formed by the tubes 22, are provided with beveled plates or vanes 29 inclined in a direction to assist in forcing the explosive mixture from the chamber 16^a into the said intake ports. To produce a forced circulation of air for cooling of the engine, the cylinder 9 is shown as provided with outstanding spiral fins or webs 30, the one being a right-hand thread and the other being a left-hand thread, and so arranged that under rotation of the cylinder in a clockwise direction in respect to Fig. 5, said fins will force the cold air toward the spiral exhaust channel 25. By reference to Fig. 5, it will be noted that the cylinder 9, adjacent to its exhaust ports 24, are provided with curved vanes or blades 31 that assist centrifugal force in forcing the exhaust gases radially outward.

Located within the chamber 16^a and freely surrounding the rotary cylinder 9 is an oblique connecting ring 32 that is set in a plane that is oblique to the axis of the cylinder, being preferably set at forty-five degrees thereto. This ring 32, as shown, has a rigidly secured sectional ball runway 32^a engaged by bearing balls 33, (see Figs. 1 and 2), that are arranged to run on an annular ball runway 34 that is set in a correspondingly oblique seat formed in the fixed intermediate outer shell section 16. The connecting ring 32 is thus mounted so that it can move only by rotation in the oblique plane in which it is set.

An oblique connecting shaft 35 is extended diametrically through the connecting ring 32 and this shaft is extended freely through diametrically opposite obliquely extended sleeves 36 that have transverse hubs 36^a. The bearing hub 36^a of one of the sleeves 36 is mounted to oscillate in a rectangular bearing or portion 12^a of the piston-connecting bar or crosshead 12, while the bearing hub 36^a of the other sleeve 36 is journaled in a rectangular bearing or portion 10^a of the sleeve piston 10. The bearing 12^a is mounted to reciprocate in longitudinal slots 9^a and 10^b formed, respectively, in the cylinder 9 and sleeve piston 10, (see Figs. 1 and 2). The bearing 10^a is mounted to slide freely in a longitudinal slot 9^b of the piston 9. In the arrangement just above described, the bearings 10^a and 12^a work much like crossheads in the cooperating slots and cause the cylinder 9, sleeve piston 10, pistons 11, and connecting bar 12 to partake of common rotary motion within the relatively fixed outer shell or casing 16—17.

An engine of the type disclosed requires ignition connections of special construction and, as shown, these are as follows: Mount-

ed in each piston 11 and exposed to the co-operating explosion chamber is a spark plug 37 of the usual or any suitable construction, one electrode of which is grounded through the engine and the other electrode of which is connected to a wire 38, (see Figs. 1, 2 and 3), are extended independently through insulating bushings 39 applied to the piston-connecting bar 12 at diametrically opposite and longitudinally spaced points. The outer ends of said wires 38 are terminated in metallic plates or heads 40. These terminal plates 40 are arranged to be brought nearly or quite into contact with terminal plates or heads 41 on the inner extremities of the lead wires 42 mounted in insulating segments 43 secured to the exterior of the cylinder 9 centrally thereof and at diametrically opposite points. Said terminal plates 41 are at diametrically opposite points and are so related that the terminal plates 40 nearly or quite brush the same at the proper time to produce sparks at the respective plugs 37. This relative location will be more clearly stated in the description of the operation. The wires 42, as shown, terminate in contact plates 44 countersunk in the insulating segments 42 and arranged to move past a common contact brush 45 shown as mounted in but insulated from a sleeve-like holder 46. To adjust the ignition system in respect to the lead, the holder 46 is shown as extended through a circumferential slot 47 in the case section 16 and is adjustably clamped thereto by nuts 48. 100

Operation.

Before following in detail the various steps in a complete cycle of operation of the engine, attention is called to the following facts:

The explosive mixture will be compressed and exploded in the spaces between the pistons 11 and the heads 27 of the sleeve piston 10, and the force of an explosion will cause the pistons proper to move in one direction and the sleeve piston to move in the other direction within the cylinder 9. In Fig. 1, the shaft 35 is shown as at its extreme angular position of forty-five degrees, in which position, the coupling mechanism is at its dead center, and if the explosion should be produced with the parts at rest while in this extreme or dead center position, the force of the explosion would be neutralized and the cylinder, sleeve piston and pistons would not be rotated in either direction. However, when the engine is under momentum, the action of the dead center will nearly or quite disappear and, moreover, the explosives will be timed so that they will occur just after the shaft 35 has passed dead center position. Here, attention is also called to the fact that when the explosion is produced and the sleeve piston and pistons are

under force to move in reverse directions at a time when the shaft 35 is off dead center, such force, transmitted to the rotary oblique ring 32, will cause said ring to rotate and, 5 of course, when the said ring rotates, the shaft 35 will travel with it and, through the connections described, the cylinder, sleeve piston and pistons proper will be caused to rotate, as already stated. Under such rotation, the piston 9 does not, of course, move axially, but the sleeve piston and pistons proper will reciprocate while partaking of a common rotation with the cylinder 9. As 10 the ring 32 rotates, the shaft 35 will change its angular position, first moving from its 15 forty-five degree inclination to the axis of the cylinder until it reaches a vertical plane when it will stand perpendicular to the axis of the cylinder, and from such perpendicular position as it continues to be rotated with the cylinder, it will again vary its angular position until it reaches its opposite dead center at a position ninety degrees from that shown in Fig. 1.

25 With the above general statements of operation, the following specific illustration of a cycle of operation will be more readily understood.

The rotation of the cylinder and parts 30 movable therewith will be in the direction of the arrows marked on Fig. 5 to wit: in a clockwise direction in respect to Fig. 5. Assume that the explosive charge has been compressed between the left-hand head 27 35 of the sleeve piston and the cooperating piston 11, and that the ring 32 has been rotated slightly beyond the dead center position of the shaft 35 shown in Fig. 1. In this position, the spark plug circuit will be closed 40 by movement of the cooperating plate 44 past the brush 45 and movement of the plate 40 past the cooperating plate or contact 41, thereby causing the spark necessary to produce the explosion. When this explosion is 45 produced, the pistons 11 will be moved toward the right and the explosive piston 10 will be moved toward the left in respect to Fig. 1. When the left-hand piston 11 passes the left-hand ports 26 of the sleeve piston 50 10, said left-hand ports 26 will be in registration with the left-hand exhaust ports 24 of the cylinder 9 and exhaust will then take place through the ports 24 and 26, as best shown in Fig. 1, and this exhaust will be 55 directed outward through the spiral exhaust channel 25 and, at the same time, cold air will be drawn inward partly by the suction produced from the exhaust and partly by the action of the spiral flange 30, thereby 60 cooling the cylinder. As soon as the gases have been exhausted from the left-hand explosion chamber, as just described, the explosive vapor compressed in the left-hand end of the cylinder 9 will cause the valve 28 65 to open, thereby transferring the explosive

charge into the space between the left-hand head 27 and left-hand piston 11. Under the movement just noted of the pistons from the left toward the right and of the sleeve piston from the right toward the left, said right-hand piston first closes the ports 26 of said sleeve piston and then compresses the charge of explosive vapor within the right-hand end of the sleeve piston 9 and 10 so that it, in turn, will be transferred to the explosion 75 chamber as soon as exhaust has been completed in the right-hand explosion chamber.

In this arrangement, it is evident that explosions in the left and right-hand ends of the sleeve piston will be alternated and will 80 take place one hundred and eighty degrees apart in respect to the rotation of the cylinder. Otherwise stated, there will be one explosion in each chamber for each rotation of the cylinder and two explosions in the 85 engine for each complete rotation or cycle of operation. When the explosion is produced in the right-hand end of the sleeve piston, the latter will be caused to move from the left toward the right while the pistons are 90 being moved from the right toward the left, and at such time, the valve 28 will be closed and the left-hand intake valve 20 will be opened, thereby drawing the new charge of the explosive mixture from the chamber 16 95 through the tubes 22 and ports 21.

At the right-hand end of the engine shown in Fig. 1, the condition illustrated is just before the exhaust has been completed, but it will be understood that just an instant later, the pressure from the exploded gases will, by exhaust, be reduced below that of the pressure of the compressed gas in the right-hand end of the cylinder and that the valve 28 will then be automatically 105 opened to permit the compressed charge to be transferred into the right-hand end of the sleeve piston 10.

The diagrammatic view 6 illustrates the same conditions that exist in Fig. 1. Fig. 110 7 illustrates the condition that exists when the cylinder has been rotated ninety degrees from the position shown in Figs. 1 and 5, and Fig. 8 illustrates a condition just opposite from that illustrated in Figs. 1 and 6, that is, a condition that exists when the cylinder has been rotated one hundred and eighty degrees from the position shown in Figs. 1, 5 and 6.

Considering further the arrangement of 120 the ignition devices, attention is called to the fact that, under the combined rotary and reciprocating movements, the contact or terminal plates 40 that are carried by the piston-connecting bar or member 12 are 125 caused to travel the lines of substantially elliptical curves drawn on a cylindrical surface. The contacts 44 rotate with but do not move axially of the rotary cylinder and, hence, they alternately pass the relatively 130

fixed contact or terminal 45 to produce the alternate explosions in the opposite ends of the cylinder. The contacts 40 are diametrically opposite but are offset longitudinally of the piston-connecting member 12 and are so located that each, in its proper order, will pass the cooperating contact 41 at the time the contact 44 for the cylinder to be fired passes the fixed contact or terminal 45. This arrangement, therefore, produces the alternate explosions in the opposite ends of the cylinder at the proper times, but the sparking instant may be advanced or retarded somewhat by circumferential adjustments of the contact or terminal 45.

The invention has above been designated as an engine, but the word "engine" is used in a very broad and liberal sense to include a device operated as a pump. When the device is to be used as a pump, rotary motion will, of course, be imparted to the cylinder by application of external force.

What I claim is:

1. An engine comprising a cylinder, piston and outer support, said piston having a reciprocating movement within said cylinder, and an oblique rotary connection between said cylinder and outer support arranged to cause rotation of one of the elements in respect to the other when said piston is reciprocated.

2. In an engine, the combination with an outer support, of a cylinder arranged to rotate within said support, a sleeve piston working within said cylinder, a piston proper working within said cylinder, and an oblique connection reacting against said support and coupled to said sleeve piston and piston proper for rotation therewith, whereby said cylinder, sleeve piston and piston proper will be rotated when said sleeve piston and piston proper are moved axially, the one in respect to the other.

3. An engine comprising a cylinder, piston and outer support, said piston having a reciprocating movement within said cylinder, and an oblique rotary connection between said cylinder and outer support arranged to cause rotation of one of the elements in respect to the other when said piston is reciprocated, the said members having cooperating ports and valves whereby the motive fluid will be introduced first into the ends of the cylinder and from thence into the explosion chamber between said piston proper and the head of said sleeve piston.

4. In an engine, the combination with an outer support, of a cylinder arranged to rotate within said support, a sleeve piston working within said cylinder, a piston proper working within said cylinder, and an oblique connection reacting against said support and coupled to said sleeve piston and piston proper for rotation therewith, whereby said

cylinder, sleeve piston and piston proper will be rotated when said sleeve piston and piston proper are moved axially, the one in respect to the other, the said members having cooperating ports and valves whereby the motive fluid will be introduced first into the ends of the cylinder and from thence into the explosion chamber between said piston proper and the head of said sleeve piston.

5. An engine comprising a rotary cylinder, a sleeve piston working within said cylinder, a piston proper working within said sleeve piston, valve-equipped ports controlling admission and exhaust to and from the chamber formed between said piston proper and the head of said sleeve piston, a connecting ring surrounding said cylinder and arranged to rotate in a plane oblique to the axis thereof, said ring being connected to impart common rotary movement to said cylinder, sleeve piston and piston and having diametrically opposite connections to said sleeve piston and piston, whereby when said sleeve piston and piston are given reverse axial movements by pressure applied between the same, said cylinder, sleeve piston and piston will be rotated.

6. In an engine, the combination with a non-rotary outer shell affording a support and a source of fluid pressure supply, of a cylinder arranged to rotate within said outer shell and provided with a valve-equipped intake port leading from said chamber, a sleeve piston working within said cylinder and provided in its head with an inwardly opening check valve, a piston working in said sleeve valve, said cylinder and sleeve piston having cooperating exhaust ports, a connecting ring mounted in said support, surrounding said cylinder and arranged to rotate in a plane oblique to the axis of the cylinder, said ring having diametrically opposite coupling devices connected one to said sleeve piston and the other to said piston proper, the said connecting ring being arranged to rotate with said cylinder, sleeve piston and piston, said sleeve piston and piston having reciprocating movements within said cylinder, and means for introducing motive fluid into the chamber of said outer shell.

7. The structure defined in claim 6 in which said cylinder has an axially projecting shaft from which rotary motion may be transmitted.

8. The combination with an outer support, of a double-ended cylinder mounted to rotate in said support, but held against axial movements, a double-ended sleeve piston working within said cylinder, a double-ended piston proper working in said double-ended sleeve piston, said cylinder and sleeve piston having ports and cooperating valves arranged to introduce the motive fluid first into the ends of said cylinder and thence through the

heads of said sleeve piston into the respective explosion chambers, and a connecting ring mounted for rotation in said support in a plane oblique to the axis of said cylinder, said ring being pivotally connected to said sleeve piston and double-ended piston, said cylinder, sleeve piston and double-ended piston being connected for common rotation and said sleeve piston and piston being free for axial movements, the one in respect to the other and in respect to said cylinder.

9. The structure defined in claim 8 in which said outer support is formed with chambers surrounding the intermediate portion of said piston and in which the fuel

10. The structure defined in claim 8 in which said cylinder and sleeve piston are provided with cooperating exhaust ports arranged to be opened approximately at the limit of the working strokes of said piston, said outer support having cylindrical portions that surround the opposite ends of said cylinder and formed with exhaust passages that surround the exhaust ports of said cylinder and open to the atmosphere.

intake ports lead from said chamber to the opposite ends of said cylinder.

10. The structure defined in claim 8 in which said cylinder and sleeve piston are provided with cooperating exhaust ports arranged to be opened approximately at the limit of the working strokes of said piston, said outer support having cylindrical portions that surround the opposite ends of said cylinder and formed with exhaust passages that surround the exhaust ports of said cylinder and open to the atmosphere.

In testimony whereof I affix my signature.

ARTHUR H. WRIGHT.
